UNITED STATES PATENT OFFICE.

HERBERT S. ATKINSON, OF EAST ORANGE, NEW JERSEY, ASSIGNOR TO THE HAYWARD COMPANY, OF NEW YORK, N. Y., A CORPORATION.

BUCKET.

1,138,614.

Specification of Letters Patent.

Patented May 11, 1915.

Application filed December 16, 1909. Serial No. 533,363.

To all whom it may concern:

Be it known that I, HERBERT S. ATKINSON, a citizen of the United States, and a resident of East Orange, in the county of Essex and

5 State of New Jersey, have invented certain novel and useful Improvements in Buckets, of which the following is a specification.

This invention relates to improvements in buckets of the class employed in excavating, 10 dredging, hoisting and conveying, and in the present instance I have shown my improvement embodied in a bucket of the type commonly known as the "clamshell" bucket.

In carrying out my invention it is my purpose 15 to provide a bucket capable of making long cuts in the material to be handled, this being a desired factor when the material is densely packed and heavy, such as iron ore, compact sand or the like.

20 A further object of my invention is to provide a bucket embodying the desired features of durability and strength, the parts and elements of the bucket being so correlated and arranged that the entire mechanism is maintained in alinement, and the strains evenly distributed throughout the bucket.

The invention consists in the construction, combination and arrangement of parts set forth in and falling within scope of the appended claims.

In the accompanying drawings, Figure 1 is a side view of a bucket embodying my improvements, the open position of the shells or bowl sections being illustrated in dotted lines; Fig. 2 is an end view of the bucket shown in Fig. 1; Fig. 3 is an enlarged detail view of the movable sheave casing arranged in the lower center of the bucket; Fig. 4 is a top view of the same; Fig. 5 is an enlarged 35 detail view in elevation of the sheave casing and sheave at the upper portion or head of the bucket; Fig. 6 is a top view of the same, also showing the manner of joining the side connecting-arms to the head casting; Fig. 7 is an enlarged detail end view of the movable 40 sheave casting, showing the connection of the side arms of the bucket thereto; Fig. 8 is a detail view, partly in section, of one form of rope thimble used in connection 45 with my invention; Fig. 9 is a sectional view showing the manner of connecting the lower ends of the side rods to the bowl sections.

In the bucket shown herein, two lines or cables are employed, one being the hoisting 50 line for supporting, and raising and lower-

ing the bucket, and the second, the closing line for closing the bowl sections upon the material. In this type of bucket, the bowl sections are so connected and arranged that the weight of the sections tends to open the bucket. The 60 closing of the bucket in this invention, is effected by means of a tackle device that is, a series of sheaves arranged in the upper and lower centers of the bucket, so that the closing rope makes a number of turns over the sheaves 65 and sufficient power is thus applied to cause the bucket to dig properly. The center sheave, in the upper center or head of the bucket, takes the bight of the two-part holding line so that the bucket can be worked in 70 the bight of the line, thereby balancing the strains on the ropes and trolley when the bucket is used in connection with bridges and cable-ways. This also permits the 75 bucket to be hoisted and trolleyed at the same time without employing a compensating device in the operating machine.

Referring now to the drawings in detail, 5—5 indicate the bowl sections or shells of the bucket which form the receptacle for the 80 load and also act as digging members. These sections are connected to the head or casting 6 by the connecting rods 7, there being in the present instance four of such rods, each pivotally connected at one end to the head 6, 85 and at the opposite end pivotally connected to the bowl sections. The manner of connecting these rods will be described in detail hereafter. The diverging truss-rods 8 are pivotally connected at their upper ends 90 to the head casting and at the lower ends to the central section of the bowl as is shown at 9.

10 indicates as an entirety a movable sheave-carrying casing or frame mounted 95 in what may be termed the lower center of the bucket, said casing carrying vertical sleeves 11 surrounding the vertical guide bars 12 fast to and depending from the head casting 6. The manner of securing these 100 guide bars 12 to the head casting will be readily understood by reference to Figs. 2 and 5. These bars are preferably tubular, and the upper portions of the same pass through borings 13 in the head casting, nuts 14 being threaded onto the ends of the bars and further secured by means of the cross-pins 15 passing through the nuts and bar. Similarly, nuts 16 are threaded onto the rods 105 below the head casting and secured by the 110

pin 17. At the lower free ends of the depending guide-bars 12 I provide heads or stops 18 preferably threaded onto the ends of the bars and secured by the cross-pins 19, these stops or heads limiting the downward movement of the sheave casing 10 and consequently determining the extent to which the bucket may open. Each of the bucket sections 5 is provided with an upwardly extending side arm 20 pivotally connected as at 21 to the movable sheave casing 10, and 22 are cross braces connecting the arms on the same bowl section. The purposes of these cross braces 22 are not only to give strength to the bucket but also to give rigidity to the bowl sections, and, in connection with the truss-rods 8, to retain the opposing bowl sections, and side arms in alinement, and this is important, since any departure of these parts from their alined positions will result in undue strain and wear on the sheave ropes.

The manner of pivoting the side arms 20 to the sheave casing 10 is clearly shown in Fig. 3, and as each arm is pivoted in the same manner, a description of one will suffice. The movable casing or casting is provided with a transverse bore 23 and the bolt 24, after passing through the shouldered collar 25, riveted to the arm, passes into this bore 23 and is threaded into the nut 26 lying in the enlargement or recess in the bore, the bolt being further secured by the pins 27 passing through the bolt and the adjacent portion of the casing. When it is desired to disconnect the arm from the casing, the pins 27 are withdrawn, the bolt unscrewed from the nut and withdrawn, and the nut then removed by means of a suitable tool inserted into the hole 28 in the nut, the nut socket or enlarged recess being an open one.

The manner of pivotally connecting the side bars 7 and the brace rods 8 to the head of casting 6 is shown in Fig. 5. The terminals or ends of the adjacent braces and rods are extended parallel and in contact, and the flanged bushings 29 have their shanks extended from opposite sides into the alining bores in the braces and rods, such bushings forming a bearing for the pin 30 extending transversely into the head and secured by cross pin 31. Said bushings are feathered to the said braces and rods so as to turn therewith, and the pin 30 carries a feather securing it against rotation to the head or casting 6. It will of course be understood that all four arms and braces may be likewise secured to the head.

The manner of pivotally connecting the lower end of each connecting rod to the bowl sections is shown in Figs. 2 and 9. Referring to the latter figure, the end of the rod is perforated or bored transversely and located between the bucket lugs 32, 32. 33 is a bushing passing through the rod and

34 are bearings fitting into the bucket lugs adjacent to the ends of the bushing. The bores of the bushings and bearings are formed with holes square in cross section, and 35 is a bolt having a square shank passing through the bearings and bushing and connecting all the parts solidly together, in such manner that they are prevented from rotating, the bored hole in the end of the connecting rod being made sufficiently large 70 to permit the connecting rod to work freely on the bushing 33. 36 is a nut on one end of the shank of the bolt, the head at the opposite end of the shank being squared and abutting against the adjacent top edge of 80 the side plate.

Referring now to Figs. 1, 2, 5 and 6, it will be seen that within the upper head casting or casting 6 is mounted the sheave frame 37. Within this frame is rotatably mounted the sheave set indicated as an entirety by letter X, preferably formed of a plurality of sections, 39, 40 and 41, all mounted on the same shaft, although, if desired, separate shafts and pins may be employed for 90 each sheave section. 42 designates the shaft for the sheave sections or members having its main bearings in the sides of the casing 10. The sheave frame 37 is divided longitudinally by the walls 39^a, 41^a, which are 95 centrally bored for the reception of the shaft 42. Said walls are secured at their ends to the end portions of the frame 37 and are surmounted by a fair-leader cap 41^b having elliptical openings 41^c. These walls 100 separate the sheave sections and, being higher than the sheaves, not only aid in confining the ropes within the score of each individual sheave but also divide the strains occurring in the head of the bucket, since they serve, at their bored portions as intermediate bearings for the shaft 42. To one end of the shaft 42 is secured an oil cup 43 communicating with the longitudinal oil duct 44 extending through the shaft. 45 110 designates transverse bores within the shaft and through which the lubricant may flow from the longitudinal oil duct to the sheave bearing. The central sheave or section 40 receives the bight of the hoisting line a, one end of which line may be secured to the trolley or other suitable point, while the opposite end is connected to the engine drum in the ordinary manner. The closing line b connects the sheave set x with the sheave set y 115 rotatably mounted in the movable or sliding casing 10 in the lower center of the frame and is arranged as follows: The sheave set y, like the sheave set x, is formed of a plurality of sheave sections or members, 46, 47 and 48, mounted upon the shaft 49, and separated by longitudinally extending walls 46^a, 48^a, the latter being centrally bored for the reception of the shaft 49 and secured at their ends to the end portions of 130

an inner frame 48^b secured to the inner side of the casing 10. These walls aid in confining the rope within the score of each individual sheave and also divide the strains occurring in the lower center of the bucket, the same serving, at their bored portions, as intermediate bearings for the shaft 49. The shaft 49 carries at one end the oil cup 50, communicating with the longitudinal oil duct 51 within the shaft, small transverse bores or ducts 52 through which the lubricant may pass to the shaft bearings, communicating with the longitudinal duct. 53 and 54 are rope thimbles diagonally mounted on the opposite side of the casing head 6, the construction of which thimbles will be described more in detail hereafter.

The closing line passes down through one thimble, say 53, and thence around the alining section or sheave member 46 of the sheave set *u*, thence up and around the side sheave member 39 in the top casing, thence down and around the central member 47 of the sheave set *y*, thence upward and over the outside sheave member 42 in the top casing, thence down and around the outer member 48 of the sheave set *y*, and thence up and through the rope thimble 54 at the right of the drawing. It will be seen that the closing rope and sheave sets *x* and *y* in the upper and lower centers of the bucket form a tackle device, the closing rope making a number of turns to generate sufficient force to close the bucket.

In Figs. 1, 2, 5 and 6 and secured at its lower end by the nut 55^b I have shown the thimbles 53 and 54 as each comprising a tubular shank 55 swiveled in the head casting 6, the head 56 of the thimbles comprising two plates spaced apart and carrying the idler rollers 57, the top edges of the plates being cut away, as at 58, to automatically guide the sheave to the bend of the rope. The thimbles being free to swivel, of course turn to accommodate the ropes and to accurately guide the same.

In Fig. 8, I have shown a slightly modified form of thimble, in this case the latter being formed to two sections, 59 and 60, the section 59 having a tongue 61 fitting in the slot 62 in the section 60. The two sections when placed together form a flaring or bell-mouth guide for the reception of the rope, and the thimble when so assembled is secured in position in the head by means of the set screws 63.

From the above description, taken in connection with the accompanying drawings, the construction and operation of my bucket will be readily understood by those skilled in the art. When the bucket is open, the parts assume the position shown in dotted lines in Fig. 1, that is to say, with the bowl sections open, and the sliding or movable lower sheave casing with its complement of

sheave members in its lowermost position and abutting against the stops or heads at the end of the guide bars 12. The closing rope and tackle is now operated by the engine drum and the jaws or bowl sections 70 are closed and drawn together, the lower central casting and sheaves being drawn upward toward the head casting. When the bucket is fully closed, both the closing and hoisting lines, through the engine, are 75 operated to hoist the bucket. The bucket is then swung to the point of discharge and the closing line slackened to discharge the load.

It will of course be understood that the 80 bowl section may be altered as to shape to suit the conditions and class of materials to be handled and that variation and modification may be made in other respects without departing from the spirit of the invention or exceeding the scope of the claims.

What I claim is:

1. A bucket comprising a supporting head, sheaves mounted in said head, co-operating bowl sections, connecting rods 90 pivotally connected to said head and to said bowl sections, guide members depending from and supported only by the head, a movable sheave casing pivotally connected to the bowl sections and having recesses to 95 receive said guide members, sheaves mounted in said movable casing, and a closing line co-operating with the sheaves in the head and those in the movable casing to raise and lower the latter and thereby open and close 100 the bowl sections.

2. The combination with a hoisting and supporting line of a bucket of the class described, comprising a supporting head, having an elongated opening diagonally disposed, a supporting sheave around which said hoisting and supporting line is adapted to pass mounted in said opening, separately rotatable bowl operating sheaves also mounted in said opening, co-operating bowl 110 sections, connecting rods pivotally connected to said head and to said bowl sections, guide members depending in parallel relation from the head, a movable sheave casing, having portions bored to receive said 115 guide members, arms on said bowl sections pivotally connected to the sides of said casing, bowl operating sheaves mounted in said casing, said head sheaves being diagonally arranged in co-operative vertical relation to 120 the bowl operating sheaves in said movable casing, and flexible means co-operating with the sheaves in the head and in the movable casing to open and close the bowl sections.

3. A bucket comprising a supporting head, sheaves mounted in said head, co-operating bowl sections, connecting rods pivotally connected to said head and to said bowl sections, guide members depending from and supported only by the head, a sheave casing 125

slidably mounted on said guide members, sheaves in said casing, side arms rigidly secured to the bowl sections and pivotally connected to the sheave casing, a 5 closing line coöperating with the sheave members in the head and those in the movable casing to raise and lower the latter and thereby open and close the bowl sections, and means on said guide-members 10 adapted to limit the downward movement of said sheave casing.

4. A bucket comprising a supporting head, sheaves mounted in said head, coöperating bowl sections, connecting rods pivotally connected to said head and to said bowl sections, guide members depending from the head and having their lower ends free, a sheave casing slidably mounted on said guide members, sheaves in said casing, side 15 arms rigidly secured to the bowl sections and pivotally connected to the sheave casing, brace members connecting said arms and divergent truss members connected to each bowl section and to the bucket head adapted 20 to retain the bowl sections in alinement, and a closing line coöperating with the sheave members in the head and those in the movable casing to raise and lower the latter and thereby open and close the bowl sections. 25

5. In combination with a bucket of the class described a supporting-head having an opening therein, a sheave casing within said opening and secured to the head, bored walls dividing said casing and supported at their 30 ends by the ends of the casing, sheaves within the divisions formed by said walls, and a shaft passing through said head, walls and sheaves, the bores of said walls acting as a bearing for said shaft.

6. In combination with a bucket, a sheave casing slidably mounted on said bucket, a frame within and secured to said casing, bored walls dividing said frame and supported at their ends by the ends of said 45 frame, sheaves within the divisions of said frame, and a shaft passing through said casing, frame and sheaves, the bores of said walls acting as a bearing for said shaft.

7. In a bucket of the class described, the 50 combination of a supporting head, coöperating bowl sections, rods extending between the head and the bowl sections, means for opening and closing said bowl sections, and means for pivotally connecting said rods to the head, comprising bored jaws on said head, flanged bushings between said jaws extending from opposite sides into bores in the ends of the rods and feathered to said rods, a pin passing through said jaws and 55 through said bushings, and means securing the pin in operative position.

8. In a bucket of the class described, the combination with a movable sheave carrying casing mounted in the lower center of 60 the bucket, of means for connecting the side

arms of the bucket to said casing, said means comprising a pin extending through bearings at the ends of said arms and through a bore in the casing, a nut lying within a recess in the casing and receiving the shank 70 of the bolt, and a transverse pin securing the bolt shank to the casing.

9. In a bucket of the class described, the combination of a supporting bucket head, coöperating bowl sections, connecting rods 75 extending between said head and the bowl sections and means for pivotally connecting the ends of said rods to the bowl sections, said means comprising a bushing extending into an aperture or bore in the end of the 80 connecting rod, lugs at either side of the connecting rod, bearings extending into said lugs, and a bolt square in cross section connecting the lugs, bearings and connecting rods, the bores or openings in said last mentioned parts being square to accommodate 85 said bolt.

10. In a bucket, the combination of a supporting bucket head, pivoted bowl sections, means for opening and closing said sections, 90 including a line, and thimbles for said line comprising a tubular shank member swiveled in the bucket head, a frame carried by said shank member having at its upper portion an opening, and a plurality of idlers 95 within said frame, said frame including means thereon adapted, by contact with said line, to deflect said frame into proper line-guiding position in any operating position assumed by the bucket.

11. In a bucket, the combination of a supporting bucket head, pivoted bowl sections, means for opening and closing said sections, including a line, and a thimble for said line comprising a tubular shank member pivotally mounted within the supporting head, a frame carried by said member and a plurality of idlers mounted within said frame, said frame having a part thereof extending upwardly above said idlers, whereby, when 105 said line contacts with said part, said frame is deflected into proper line-guiding position in any operating position of the bucket.

12. In a bucket, the combination of a supporting bucket head, pivoted bowl sections, 110 means for opening and closing said sections, including a line, and a thimble for said line comprising a rotatable tubular shank disposed through an opening in the head, a frame carried by said shank having at its 115 upper portion an opening and a plurality of idlers carried by said frame, said frame being provided with downwardly diverging curved upper surfaces.

13. In a bucket, the combination of a supporting bucket head, pivoted bowl sections, 120 means for opening and closing said sections, including a line, and a thimble for said line comprising a rotatable tubular shank disposed through an opening in the head, a 125 130

frame carried by said shank, having at its upper portion an opening and a plurality of idlers carried by said frame disposed on approximately the same horizontal plane 5 and rotating on horizontal axes, said frame being provided with curved downwardly diverging upper surfaces.

14. A bucket of the kind described comprising a supporting - head, sheaves rotatably mounted in said head, coöperating load-trays, links pivotally connected to said head and to said trays, guide members depending from said head, a frame pivotally connected to said trays and provided with 10 portions fitting on said guide members, sheaves rotatably mounted in said frame, and flexible means adapted to coöperate with said head and frame sheaves to raise and lower said frame to close and open said trays, said 15 frame being adapted to slide below said head on said guide members on the opening and closing of said trays; substantially as described.

15. A bucket of the kind described comprising a supporting - head, coöperating load-trays adapted to open and close pivotally connected to said head, independently rotatable sheaves mounted in said head, rods depending from said head, a box-shaped casting pivotally connected to said trays and provided with bored portions fitting on said rods, independently rotatable sheaves arranged in said casting, and flexible means adapted to coöperate with said sheaves to 20 raise and lower said casting to close and open said trays, said casting being adapted to slide on said rods on the opening and closing of said trays; substantially as described.

16. A bucket of the kind described comprising a supporting - head, coöperating load-trays, links pivotally connected to said head and said trays, rods depending from said head, a box-shaped casting provided with bored portions fitting on said rods, 25 arms fixedly mounted on said trays pivotally connected to the sides of said casting, independently rotatable sheaves mounted in said head, independently rotatable sheaves arranged in said casting, and flexible means adapted to coöperate with said sheaves to raise and lower said casting to close and open said trays, said casting being adapted to slide on said rods on the opening and closing of said trays; substantially as described.

17. A bucket of the kind described comprising a supporting - head, coöperating load-trays, links pivotally connected to said head and to said trays, rods depending in parallel relation from said head, a box-shaped casting provided with bored portions fitting on said rods, arms fixedly mounted on said trays pivotally connected to the sides of said casting, independently 30 rotatable sheaves arranged in said head, in-

dependently rotatable sheaves arranged in said casting, and flexible means adapted to coöperate with said sheaves to raise and lower said casting to close and open said trays, said casting being adapted to slide on 70 said rods on the opening and closing of said trays; substantially as described.

18. A bucket of the kind described comprising a supporting - head provided with an elongated opening diagonally disposed, 75 a set of independently rotatable sheaves arranged in said opening, coöperating load-trays, links pivotally connected to said head and to said trays, rods depending in parallel relation from said head, a box-shaped frame 80 provided with portions fitting on said rods, a set of independently rotatable sheaves arranged in said frame, said head-sheaves being diagonally arranged in coöperative vertical relation to said frame-sheaves, arms fixedly mounted on said trays pivotally connected to the sides of said frame, and flexible means adapted to coöperate with said sets of sheaves, said frame being adapted to slide on said rods on the opening and closing 85 of said trays; substantially as described.

19. In a bucket, the combination with a supporting-head, of coöperating load-trays adapted to open and close having pivotal connection with said head, sheaves rotatably mounted in said head, rods depending in parallel relation from said head and having their lower ends free, a frame having pivotal connection with said trays slidably mounted on said rods, sheaves rotatably mounted in said frame, and flexible means adapted to coöperate with said sets of sheaves to open and close said trays; substantially as described.

20. In a bucket, the combination with a supporting-head, of coöperating load-trays adapted to open and close having pivotal connection with said head, sheaves rotatably mounted in said head, rods depending in parallel relation from said head and having their lower ends free, a frame having pivotal connection with said trays loosely arranged on said rods and adapted to slide thereon on the opening and closing of said trays, sheaves rotatably mounted in said frame, flexible means adapted to coöperate with said sets of sheaves to open and close said trays, and means on the end of each of said rods adapted to limit the downward movement of said frame and its carried 100 110 115 sheaves on the opening of said trays; substantially as described.

21. In a bucket, the combination with a supporting-head, of coöperating load-trays, links pivotally connecting said trays to said head, sheaves rotatably mounted in said head, rods depending in parallel relation from said head and having their lower ends free, a frame loosely arranged on said rods and adapted to slide thereon on the opening 120 125 130 of said trays; substantially as described.

and closing of said trays, arms fixedly mounted on said trays pivotally connected to said frame, sheaves rotatably mounted in said frame, flexible means adapted to co-operate with said sets of sheaves to open and close said trays, and a collar on each of said rods adapted to limit the downward movement of said frame and its carried sheaves on the opening of said trays; substantially as described.

22. The combination with a supporting-cable, of a bucket of the kind described, the same comprising a supporting-head provided with an elongated opening, a supporting-sheave around which said cable is adapted to pass rotatably mounted in said opening, a set of independently rotatable tray-operating sheaves also mounted in said opening, coöperating load-trays, links pivotally connected to said head and to said trays, rods depending in parallel relation from said head, a box-shaped frame provided with portions fitting on said rods, said frame being adapted to slide on said rods on the opening and closing of said trays, a set of independently rotatable tray-operating sheaves arranged in said frame, arms on said trays pivotally connected to the sides of said frame, and flexible means adapted to co-operate with said tray-operating sheaves to open and close said trays; substantially as described.

23. A bucket of the kind described comprising a supporting-head, coöperating load-trays, links pivotally connected to said head and to said trays, sheaves rotatably mounted in said head, guide-members depending from said head between said links, a sheave-frame pivotally connected to said trays and slidably movable on said guide-members below said head, sheaves rotatably mounted in said frame, and flexible means adapted to co-operate with said sheaves to open and close said trays; substantially as described.

45 24. A bucket of the kind described comprising a supporting-head, coöperating load-trays, links pivotally connected to said head and to said trays, sheaves rotatably mounted in said head, a pair of parallel guide rods depending from said head between said links, a sheave-frame pivotally connected to said trays and slidably movable on said rods below said head, sheaves rotatably mounted in said frame, and flexible means adapted to coöperate with said sheaves to open and close said trays; substantially as described.

50 25. A bucket of the kind described comprising a supporting-head, coöperating load-trays, links pivotally connected to said head and to said trays, rods depending from said head between said links, a sheave-frame slidably arranged on said rods, arms fixedly connected to said trays and pivotally connected to said frame, sheaves rotatably mounted in said head, sheaves rotatably mounted in said

frame, and flexible means adapted to coöperate with said sheaves to open and close said trays; substantially as described.

26. A bucket of the kind described comprising a supporting-head, coöperating load-trays, links pivotally connected to said head and to said trays, rods depending from said head, a sheave-frame provided with portions fitting on said rods, arms fixedly connected to said trays and pivotally connected to the sides of said frame, sheaves rotatably mounted in said head, sheaves rotatably mounted in said frame, and flexible means adapted to coöperate with said head and frame sheaves to raise and lower said frame to close and open said trays, said frame being adapted to slide on said rods on the opening and closing of said trays; substantially as described.

27. A bucket of the kind described comprising a supporting-head, coöperating load-trays, links pivotally connected to said head and to said trays, sheaves rotatably mounted in said head, guide-members depending from said head between said links, a box-shaped casting pivotally connected to said trays and having bored portions fitting on said guide members, sheaves rotatably mounted in said casting, and flexible means adapted to co-operate with said sheaves to raise and lower said casting to close and open said trays, said casting being adapted to slide on said guide-members below said head on the opening and closing of said trays; substantially as described.

28. A bucket of the kind described comprising a supporting-head, coöperating load-trays, links pivotally connected to said head and to said trays, sheaves rotatably mounted in said head, rods depending from said head, a box-shaped casting having bored portions fitting on said rods, arms fixedly connected to said trays and pivotally connected to said casting, sheaves rotatably mounted in said casting, and flexible means adapted to co-operate with said sheaves to raise and lower said casting to close and open said trays, said casting being adapted to slide on said rods on the opening and closing of said trays; substantially as described.

29. A bucket of the kind described comprising a supporting-head, provided centrally with a diagonally-disposed opening, a set of sheaves rotatably arranged in said opening, coöperating load-trays, links pivotally connected to said head at the ends thereof and to said trays, guide-members depending from said head, a sheave-frame provided with portions fitting on said guide-members, a set of sheaves rotatably mounted in said frame, said head-sheaves being diagonally disposed in coöperative vertical relation to said frame-sheaves, arms mounted on said trays and pivotally connected to said frame, and flexible means

adapted to coöperate with said head and frame-sheaves to open and close said trays, said frame being adapted to slide on said guide-members on the opening and closing 5 of said trays; substantially as described.

30. A bucket of the kind described comprising a supporting-head provided centrally with a diagonally-disposed opening, a set of sheaves rotatably arranged in said 10 opening, coöperating load-trays, links pivotally connected to said head at the ends thereof and to said trays, rods depending from said head between said links and at opposite ends of said diagonally-disposed opening, a 15 box-shaped sheave-frame provided with portions fitting on said rods, a set of sheaves rotatably mounted in said frame, said head-sheaves being diagonally disposed in coöperative vertical relation to said frame-sheaves, 20 arms mounted on said trays and pivotally connected to said frame, and flexible means adapted to coöperate with said sets of sheaves to open and close said trays, said frame being adapted to slide on said rods on 25 the opening and closing of said trays; substantially as described.

31. A bucket of the kind described comprising a supporting-head, sheaves rotatably mounted in said head, coöperating load-trays, diverging pairs of links pivotally connected at their opposite ends to said head and to said trays, guide-members depending from said head, a sheave-frame having portions fitting on said guide-members, sheaves 30 rotatably mounted in said frame, side arms rigidly secured to said trays and pivotally connected to said frame, brace-members connecting said arms, and flexible means adapted to coöperate with said head- and frame-sheaves to open and close said trays, said frame being adapted to slide on said guide-members on the opening and closing of said 40 trays; substantially as described.

32. A bucket of the kind described comprising a supporting-head, sheaves rotatably mounted in said head, coöperating load-trays, diverging pairs of links pivotally connected at their opposite ends to said head and to said trays, rods depending from said 45 head and having their lower ends free, a sheave-frame slidably mounted on said rods, sheaves rotatably mounted in said frame, arms rigidly secured to said trays and pivotally connected to said frame, brace-members 50 connecting said arms, and flexible means adapted to coöperate with said head and frame-sheaves to open and close said trays, said frame being adapted to slide on said rods on the opening and closing of said 55 trays; substantially as described.

33. The combination with a supporting-cable, of a bucket of the kind described, the same comprising a supporting-head provided centrally with an enlarged opening, a 60 supporting-sheave around which said cable

is adapted to pass rotatably mounted in said opening, tray-operating sheaves also rotatably mounted in said opening, coöperating load-trays, links pivotally connected to said head at the ends thereof and to said trays, 70 rods depending in parallel relation from said head at opposite ends of said enlarged opening and between said links, a sheave-frame having portions fitting on said rods, tray-operating sheaves rotatably mounted 75 in said frame, arms on said trays pivotally connected to said frame, and flexible means adapted to coöperate with said tray-operating sheaves to open and close said trays, said frame being adapted to slide on said rods 80 on the opening and closing of said trays; substantially as described.

34. The combination, in a bucket of the kind described, with a supporting-head having an opening therein, of a sheave casing 85 arranged within said opening and secured to said head, bored walls dividing said casing and secured at their ends to the ends of said casing, a shaft mounted in said head and passing through said head, casing, and 90 walls, and sheaves rotatably mounted on said shaft within the divisions formed by said walls; substantially as described.

35. The combination, in a bucket of the kind described, with a supporting-head having an opening therein, of a sheave casing arranged within said opening and secured to said head, said casing comprising side walls and intermediate walls, said side walls being bent at opposite ends and secured together and to said casing and said intermediate walls dividing the space between said side wall and being secured at their ends to the bent ends of said side walls, a shaft mounted in said head and passing through 95 said head and walls, and sheaves rotatably mounted on said shaft within the divisions 100 formed by said intermediate walls; substantially as described.

36. The combination, in a bucket of the kind described, with a supporting-head having an opening therein, of a sheave casing arranged within said opening and secured to said head, said casing comprising side walls and intermediate walls, said intermediate walls dividing the space between said side walls into central and outer divisions, a shaft mounted in said head and passing through said walls, a bucket-supporting 110 sheave rotatably mounted on said shaft within said central division, and tray-operating sheaves rotatably mounted on said shaft within said outer divisions; substantially as described.

37. The combination with a bucket of the kind described having a lower sheave-frame, of a sheave casing arranged in and secured to said frame, said casing comprising side walls, end walls, and intermediate 115 walls, said side and end walls being secured 120

65 walls, said side and end walls being secured 125

together and to said frame and said intermediate walls dividing the space between said side walls into divisions and being secured at their ends to said end walls, a shaft 5 mounted in said frame and passing through said side and intermediate walls, and sheaves rotatably mounted on said shaft within the

divisions formed by said intermediate walls; substantially as described.

HERBERT S. ATKINSON.
